(57) **CLAIM**

The ornamental design for a computer pointing device, as shown and described.

DESCRIPTION

This patent application is related to three other applications for Computer Pointing Devices, each by the same inventor and each being filed separately on this same day.

FIG. 1 is a side view of my computer pointing device.

FIG. 2 is an opposite side view of my computer pointing device

FIG. 3 is front view of my computer pointing device.

FIG. 4 is top view of my computer pointing device.

FIG. 5 is bottom view of my computer pointing device; and,

FIG. 6 is rear view of my computer pointing device.
